(57) **CLAIM**

The ornamental design for a glass cleaning tool, as shown and described.

DESCRIPTION

FIG. 1 is a front right perspective view for a glass cleaning tool;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines in the figures represent portions of the glass cleaning tool that form no part of the claimed design.

1 Claim, 7 Drawing Sheets
